CLAIM

The ornamental design for a palm pad for a glove for prevention of carpal tunnel syndrome, as shown and described.

DESCRIPTION

FIG. 1 is a front elevation view of a palm pad for a glove for prevention of carpal tunnel syndrome showing my new design;

FIG. 2 is a right side elevation view thereof;

FIG. 3 is a left side elevation view thereof;

FIG. 4 is a top plan view thereof;

FIG. 5 is a bottom plan view thereof; and,

FIG. 6 is a sectional view taken along the line 6—6 in FIG. 1.

The rear elevation view of the pad is a mirror image of the front elevation view without the diamond shaped pad projections. The broken line illustration of a glove is for illustrative purposes only and forms no part of the claimed design.

The broken lines defining the diamond pattern in FIG. 1 illustrate impressions in the covering material made by the underlying pad projections.
